UNITED STATES PATENT OFFICE

140,144

DESIGN FOR A SCARF

John Lavalle, United States Army, assignor to The United States of America, as represented by the Secretary of War

Application September 30, 1944, Serial No. 115,534

Term of patent 3½ years

(CL. D3—12)

To all whom it may concern:

Be it known that I, John Lavalle, a citizen of the United States who is in the United States Army, have invented a new, original, and ornamental
Design for a Scarf, of which the following is a specification, reference being had to the accompanying drawing, forming a part thereof, in which:

The figure is a plan view of a scarf showing my new design.

I claim:

The ornamental design for a scarf, as shown.

JOHN LAVALLE,
